UNITED STATES PATENT OFFICE.

LEOPOLD KACZANDER, OF NEW YORK, AND ROBERT RUDDY, OF MOUNT VERNON, ASSIGNEES TO THE NATHAN MANUFACTURING COMPANY, OF NEW YORK, N. Y.

STUFFING-BOX FOR STEAM-VALVES.

SPECIFICATION forming part of Letters Patent No. 359,869, dated March 22, 1887.

Application filed December 23, 1886. Serial No. 222,349. (No model.)

To all whom it may concern:

Be it known that we, LEOPOLD KACZANDER, of the city, county and State of New York, and ROBERT RUDDY, of Mount Vernon, West Chester county, and State of New York, have invented certain new and useful Improvements in Yokes and Stuffing-Boxes for the Spindles of Steam-Valves, of which the following is a specification.

Our invention has particular reference to yokes, stuffing-boxes, and valves used with injectors, or, with injector-starting valves, where it is desirable to locate the threaded part of the valve-spindle outside of and away from the steam-chamber, in order to prevent the contact between the threaded part of the spindle and the steam, thereby lessening the wear and tear, and causing the spindle to last longer. However, our improvement can be applied not only to injector-valves, but to any kind of steam-valves and their spindles whenever the location of the threaded part of the spindle at a distance from the steam-chamber is desirable.

Yokes and stuffing-boxes as heretofore constructed have customarily contained two or more threaded pins screwed into the yoke-body, which pins served as guides for the gland or follower; and this latter has been pressed into the stuffing-box by two or more nuts engaging with the above-mentioned pins and bearing against the flanged part of the gland. This construction requires a certain amount of space for the application of wrenches when the nuts are to be tightened, which, especially in the case of injectors, is seldom to be had, as injectors, as a general rule, are placed very close to the boiler, and at least one of the stuffing-box nuts will be so situated that it will be very difficult to place a wrench between it and the boiler. Furthermore, this construction requires a certain amount of skill in effecting the packing, as it is necessary to tighten all the nuts uniformly. If this is not done, the gland might be pushed in one-sided, causing unnecessary friction and a bad leaky packing. It has also been proposed to press the gland into its box by means of a single central pressure-nut screwing upon a neck

through which the valve-stem passes; but in this plan the nut has been caused to act upon the gland through the intermediary of separate push-pins interposed between the gland and the nut. These push-pins, being loose or separate from both the gland and the nut, have required guides through which they must pass, and in which they must fit snugly in order both to prevent them from cramping and to cause them to press evenly and uniformly on the gland. This construction enhances the cost of manufacture and detracts materially from the simplicity of the device, and is not at all times reliable.

The object of our invention is to avoid all these inconveniences, to render the construction simpler, to make the act of packing independent of the individual skill of the engineer, and to make it reliable and uniform under all circumstances.

The nature of our invention will be best understood by reference to the accompanying drawings, in which—

Figure 1 is an exterior view of our improved yoke and stuffing-box, representing its application to a common globe steam-valve, shown sectionally in dotted lines. Fig. 2 is a section on line 1 1, Fig. 1. Fig. 3 is a section on line 2 2, Fig. 1, omitting the globe and its connections.

The yoke proper consists of the part *a*, slotted at the points *b* to receive a spanner-wrench, by means of which the yoke is screwed into the injector, valve-body, or any other valved steam-chamber; and it further consists of the cylindrical part *c*, threaded externally to receive a packing-nut, *e*, and a lock-nut, *f*, and also threaded internally to form the nut for the threaded portion of the valve-spindle *A*, which on one end is provided with a suitable handle, *i*, and on the other end with a valve-disk, *k*. The parts *a* and *c* are firmly bound together by two bars, *d*. The cylindrical gland *g* is provided with two wings, *h*, which engage with a circular groove cut in the packing-nut *e*. The plug *a* is externally screw-threaded, so that it may readily be screwed into a valved steam-chamber, and it is formed with the internal packing box or chamber, *l*. Thus the yoke

contains in itself all the elements needed for a complete stuffing-box. It will now be seen that by simply screwing up the nut *e* the gland *g* will be moved forward centrally, and will 5 press uniformly on the packing material, which is placed into the hollow box *l*, Fig. 3. By unscrewing the nuts the gland can be pulled back easily, and the valve repacked, if necessary. This construction of the yoke and gland 10 combined requires, therefore, no other manipulation but the tightening or loosening of a central nut, and is consequently very simple, requiring no skill or special care in packing the valve. The gland will always press uniformly 15 on the packing material, and is therefore reliable under all circumstances.

By means of the circular groove the wings *h* are guarded against spreading, and are kept in a central position, which is very material 20 for the effective working of the apparatus. At the same time the circular groove allows the nut to be rotated freely relatively to the wings *h*. Besides the groove, other devices might be employed for the same purpose; but 25 we prefer the circular groove on account of its simplicity.

The lock-nut *f* has merely the purpose of preventing the packing-nut *e* from getting loose.

30. What we claim herein as new, and of our own invention, is as follows:

1. A yoke consisting of an externally-screw-threaded plug or part, *a*, adapted to screw into a valved steam-chamber and formed with 35 the packing chamber or box *l*, and an internally and externally screw-threaded part, *c*, constituting the spindle upon the exterior of which the packing-nut can screw, and the nut through which the valve-spindle can screw, 40 the two parts being connected by legs or bars, as *d*.

2. The combination, with the yoke consisting of the externally-screw-threaded plug or part *a*, the tubular part *c*, and the connecting 45 legs or bars *d*, of the packing-nut screwing upon the exterior of the part *c* and the packing-gland provided with wings or prolongations upon which the nut may bear, said wings or prolongations being rigidly attached to or

formed in one with the gland, substantially as 50 and for the purposes hereinbefore set forth.

3. The combination of the yoke, the packing-nut formed on its bearing-face with an annular groove, and the packing-gland provided with wings which enter and engage said groove, 55 substantially as described, whereby the packing-nut, while steadyng and centering the gland, is free to rotate independently of the latter, substantially as and for the purposes set forth. 60

4. The combination of the yoke consisting of a plug adapted to screw into a valved steam-chamber and a tubular internally and externally screw-threaded part, *c*, connected to said plug by legs or bars, as described, with a valve-spindle screwing through said part *c*, a packing-nut screwing upon the exterior of said part *c*, and a packing-gland formed in one with or rigidly attached to wings or prolongations against which the nut will bear, all substantially as and for the purposes hereinbefore set forth. 65 7c

5. The combination of a stuffing-box, a packing-nut, a screw-threaded support on which the same is mounted, and a packing-gland 75 formed in one with or rigidly attached to wings or projections upon which the nut bears, arranged substantially as hereinbefore shown and described, to cause the pressure from the nut to be distributed evenly upon the gland at 80 all points.

6. The combination of a stuffing-box, a packing-nut provided with an annular guide or centering-groove on its bearing-face, a screw-threaded support for said nut, and a gland 85 provided with wings or projections which enter said groove, and are arranged substantially in the manner hereinbefore indicated, so as to distribute evenly upon the gland the pressure of the nut, substantially as and for the purposes set forth. 90

In testimony whereof we have hereunto set our hands this 16th day of December, 1886.

LEOPOLD KACZANDER.
ROBERT RUDDY.
